34 Claims. (Cl. 178—4)

This invention relates to printing telegraph equipment and systems therefor and has particular reference to transmission and reception mechanisms for such systems wherein is employed the well known five unit Baudot code.

With the increasing use of interoffice telegraphy and integrated data processing systems, it is advantageous to transmit the units of a code group in simultaneous form over a plurality of wires. By using simultaneous transmission, less complex and higher speed translators can be used at the various receiving machines. Along with the use of simultaneous transmission systems, above referred to, it may be desired and is often necessary to transmit the same code in conventional sequential form to other apparatus in the system or to a telegraph line for distant communication.

The structure of this invention includes keyboard transmitting equipment that can transmit the units of a code in sequential arrangement and simultaneous arrangement. Both forms of transmission can be sent at the same time or either form can be sent independently to the exclusion of the other by appropriate positioning of a switching control system. The keyboard transmitter includes features such as a space counter to monitor the number of character and space transmissions and a tabulating mechanism for convenient transmission of tabulated signal groups for columnar printing. A translating mechanism capable of receiving and translating either form of signals, sequential or simultaneous, which can be transmitted by the keyboard transmitter is incorporated for disclosure purposes in a reperforator structure. Controls between the keyboard transmitter and the receiving translator enable various combinations of transmission and reception and primary control of the coordination of operation between the keyboard and translator rests in one or the other, dependent upon the form or forms of signal transmission and the form of signal reception dictated by the switching control system.

Accordingly, a primary object of this invention resides in the provision of a novel telegraph keyboard transmitter adapted to the transmission of either or both simultaneous and sequential forms of the Baudot or similar codes.

Another object of this invention resides in the provision of a novel receiving mechanism adapted to the reception of either of the above simultaneous or sequential codes.

A further object resides in providing novel coordinated means between a keyboard transmitter and a receiving printer which will result in a freer feeling to the use of the keyboard than is normally encountered in prior art transmitting equipment of this nature.

It is a still further object to provide a switching system whereby a number of related telegraph units may be used in conjunction with the equipment of this invention to provide a large number of different forms of operation and thus greatly increase the versatility of this invention over prior art forms.

2

Still another object resides in providing a novel combination of a keyboard transmitter capable of transmitting either or both sequential and simultaneous code units and a printer to receive either sequential or simultaneous code units. As a corollary to this object the novel printer can be embodied in a printing reperforator. This combination can be arranged so the keyboard concurrently transmits sequential signals to a line and simultaneous signals to a local printer or the novel combination can be so arranged that the manipulable speed of keyboard operation is limited only by the speed of the novel receiving mechanism in the printer.

A further object resides in the provision of a novel keyboard transmitter with provisions to transmit sequential code signals and/or simultaneous code signals to a receiver in which the start and stop control during any sequential transmission is in the keyboard and during solely simultaneous transmission by the keyboard is partially in the receiver.

Further objects reside in the provision of novel keyboard transmitter components to enable trouble free simultaneous transmission. A novel two position simultaneous switch bank, novel plug in printed circuits for the switch bank and novel sliding switch contacts are some of the inventive components developed in the simultaneous transmission mechanism of the keyboard transmitter.

A still further object resides in the provision of a novel solenoid controlled transmitter stop mechanism. This solenoid control enables multiple unit parallel control of the transmitter stop mechanism and thus leads to the novel coordination between the keyboard, its space counting and tabulating mechanism and the novel receiving mechanism whereby the transmitter stop mechanism can be actuated by the transmitter, the tabulating mechanism or the receiver dependent upon the control system desired.

Another object resides in the provision of novel tabulating mechanism, structurally and functionally cooperating with a keyboard transmitter to enable rapid transmission of tabulation indicia for sending data in columnar form. Together with this object, novel provision is made for automatically actuated tabulation transmission upon depression of a repeat key lever with a code key lever, which can be rendered inoperative if desired.

Still another object resides in the novel provision of a transmission spacing indicator mechanism with components in structural cooperation with the aforementioned tabulation mechanism to cause cessation of tabulation transmission when the indicator mechanism reaches a selectable predetermined space indicia position. As previously noted, this tabulation and indicating mechanism control of transmission is enabled through parallel circuitry to the novel solenoid controlled transmitter stop mechanism.

Further novel features and other objects of this invention will become apparent from the following detailed description, discussion and the appended claims taken in conjunction with the accompanying drawings showing preferred structures and embodiments, in which:

GENERAL DESCRIPTION

The equipment embodied in this invention consists of a telegraph keyboard basically similar to that disclosed in E. E. Kleinschmidt et al. application S.N. 241,916, now Patent No. 2,773,931, for Printing Telegraph Apparatus, with a keyboard operated sequential code unit transmitter substantially similar to that disclosed in the E. F. Kleinschmidt et al. U.S. Patent No. 2,754,364. As disclosed in the aforementioned patents, pressing of a key moves five permutation bars to left and right hand positions indicative of "space" (no-current) and "mark" (current) conditions of the code. A sixth bar is invariably moved to the right by the pressing of a key, and is instrumental in releasing a transmitter camshaft to make one-half revolution. As the camshaft revolves, six cam lobes are presented in sequential order to six cam followers and the cam followers are conditioned, by the permuted positions of the code bars, to allow one or the other of their ends to be raised by the passage of the associated cam lobes. This selected raising of one or the other ends of a follower causes an electrical contact to be closed or opened to provide a sequence of timed current or no-current electrical conditions to be transmitted over a single wire line. Seven of these pulses make up a code signal for each of thirty-two different combinations; the first

pulse is always one of no-current, the succeeding five pulses are permutatively selective and the seventh pulse is invariably a current pulse. After the camshaft has made one-half revolution, in which time the seven pulses are transmitted, it is stopped and will be ready for the next key to be depressed for transmission of the next code signal. The speed of the transmitter camshaft is synchronized with the receptive speed of the associated telegraph equipment and is normally in the order of 60-words per minute. Using the transmitter, as briefly described above, sequential signals may be sent out on the line and the message may be monitored on a local page printing machine such as the one disclosed in aforementioned Patent No. 2,773,931.

It has been found that for more economical use of line time and for smoother operation of the receiving equipment, it is advantageous to store the messages, produced by the keyboard, for future transmission. Message storage can be accomplished in various ways, e.g., holes punched in a paper strip or magnetic spots on a steel tape. In the present invention, storage of messages is performed by a perforator which prints a type character and punches code holes in the tape. The perforator has two coordinated receiving mechanisms, one of which is adapted to receive incoming sequential signals from a line and the other of which is adapted to receive simultaneous signals directly from the keyboard. The new keyboard transmitter of the present invention includes the basic keyboard structure of the aforementioned U.S. Patent No. 2,754,364 but the left side of the keyboard transmitter includes a simultaneous switch mechanism which is controlled by the movement of the code bars. Each code bar will move a switch member to the left or right according to the code condition, then simultaneously completing a group of permuted "mark" or "space" connections to a solenoid structure at the perforator, which is adapted to these simultaneous circuits and will operate to translate the code to mechanical conditions and record it on the tape.

When the equipment is used for only simultaneous transmission and reception, the perforator may be operated at a speed greater than the normal typing speed so the typist may manipulate the keyboard in the same free manner as used in operating an electric typewriter. This feature constitutes quite an advantage particularly when the message is being stored for future transmission on a single line and especially for operators who are not used to the restricted speed of a conventional telegraph keyboard.

The coded tape, which contains the stored message, may be subsequently fed to a tape transmitter, a suitable transmitter being disclosed in the E. F. Kleinschmidt U.S. Patent application S.N. 399,548, filed Dec. 21, 1953, now Patent No. 2,923,769, wherein the coded tape is read and sequential signals placed on the transmission line. These outgoing signals may be monitored by the local perforator through its sequential receiver or they may be monitored by a local page printer in which case the perforator will be free to record incoming messages or to store further messages from the local keyboard.

The sequential receiver of the perforator includes the conventional single relay receiver, with selecting levers, Y-levers and transfer T-levers similar to receiving structure shown in the above referred to U.S. Patent No. 2,773,931. In this invention, the sequential receiver cooperates with associated mechanism to translate the incoming sequential pulses into simultaneous switch positions which in turn operate the simultaneous receiver of the perforator which has been briefly referred to.

Using the mechanisms of this invention, as briefly described above, a number of forms of operation are possible, the most useful ones being listed below:

- (1) The keyboard sequential transmitter can be used to send directly to the signal line;
- (2) The perforator can receive a message directly from the signal line and punch and print tape.

(3) The keyboard transmitter and the perforator can be connected in series so that a message originating at the keyboard will be recorded by the perforator in punched and printed form.

(4) A page printer and the keyboard can be connected in series and wired into one line; the perforator and transmitter-distributor can be connected in series and wired into a second line. With this arrangement the keyboard transmitter can be used to send a message on one line while the page printing mechanism types a page copy of the message and the transmitter-distributor can be used to send a message on the other line while the perforator monitors the message.

(5) The keyboard simultaneous transmitter may be wired in parallel with a number of local data processing or other business machines and the perforator can monitor the data or message on punched and printed tape.

Other forms of operation may suggest themselves from the above brief description and from the detailed description which follows:

THE KEYBOARD TRANSMITTER

As schematically represented in Figure 1, a transverse code bar 20, which is one of five contained in the keyboard transmitter, as basically disposed in Patent No. 2,754,364, is shown in its right hand position, having been moved there or selected by the downward motion of a key lever 22 acting against the sloping surface 24 of an associated notch in code bar 20. At the right-hand end of the upper edge of code bar 20, a notch 26 receives the lower end 28 of a sensing lever 30 (one of five) which is pivoted on a post 32 fixed to the keyboard frame. Each sensing lever 30 has an upwardly extending finger 34 with a lateral end projection 36 serving as a latch for an associated selector lever 38 (of which there are five) to be described. In the illustrated position of code bar 20, its sensing lever 30 has been moved counterclockwise on pivot post 32 to place the end latch projection 36 in engagement above a cooperating latch shoulder 40 of the selector lever 38. Selector lever 38 has an inverted U-shaped portion 42, at its left hand end, mounted upon a square shoe 44 which in turn is pivoted on a fixed post 46. The U-shaped end portion 42 slides easily up and down upon square shoe 44 and is biased downwardly by a spring 48 attached to one of the depending legs 50 of the U-shaped portion 42. Disposed on the bottom between the ends of the lever 38 is a V-shaped cam follower 52 to be engaged by a cam lobe 54 of a cam 56, of which there are five, which in turn is carried on a shaft 58 and rotated in a clockwise direction.

On the upper edge of each selector lever 38, over the U-portion 42, is a projection 60 disposed to move in a path to engage the left hand end 62 of a rocking member 64 which is pivoted on a post 66 and biased counterclockwise by a spring 68. The rocking member left hand end 62 overlies the upper projections 60 of all five selector levers 38. On top of end 62 of rocking member 64 is an insulated electrical contact 70 connected to a source of positive electrical potential. A mating electrical contact, shown schematically by the arrow 72 in Figure 1, is above rocking member contact 70, the pair of contacts being normally open. Connection is made from contact 72 to the signal line. As will be understood from this description, with the levers 30 and 38 in the positions indicated, each time the cam lobe 54 passes the follower 52 it will press upwardly on the lever 38 at this mid-point. As the right hand end 40 of the illustrated selector lever 38 is latched by the latch end 36 of sensing lever 30, the selector lever end 40 cannot rise. The left end 42 of the selector lever 38 will therefore rise against the bias of spring 48, sliding on the shoe 44. Projection 60 engages end 62 of rocking member 64, contact 70 will be raised to engage the contact 72 and a

short duration pulse of current will be transmitted over the signal line. Had the code bar 20 been moved toward the left rather than the right, the sensing lever 30 would be moved clockwise and the associated lever 38 would not be latched at 40. Under this latter condition the cam lobe 52 will raise the righthand end of the selector lever 38, the lefthand end being held down by spring 48, and consequently the contacts 70 and 72 will not be engaged and no current pulse will be transmitted.

The above described sequence is the basis for transmitting one bit of the Baudot code. Each time a key lever is depressed a sequence of five of these bits is sent, the transmitting mechanism being initiated by the moving to the right of a universal bar 80, the end of which can be seen in Figure 2. Universal bar 80 strikes an adjusting screw 82 at the lower end of a locking lever latch 84 which is pivoted on a fixed stud 86 and biased clockwise by a spring 88. An arcuate surface 90 on the locking lever latch 84, above its pivot, has its center on the pivot axis. A bent extension 91 on the righthand end of a cam stop lever 92, is disposed to normally rest on the arcuate surface 90 of the locking lever latch 84. Cam stop lever 92 is fixed on a pivotally mounted post 94 and has a pawl end 96 which can be disposed in the path of a stop tooth 98 on a cam 100 fixed on the end of rotatable camshaft 58. Camshaft 58 is frictionally driven and will be held against rotation by engagement of the cam stop lever pawl 96 with the cam stop tooth 98. However, when the universal bar 80 is moved to the right, the locking lever latch 84 is pivoted counterclockwise to remove arcuate surface 90 from under the cam stop lever 92 which, being biased clockwise by a spring (not shown), rotates out of blocking position with cam stop tooth 98 and the camshaft 58 is released to make one-half a revolution. During this one-half a revolution, five cam lobes 54 plus a sixth cam lobe (not shown) sequentially engage and move past cam followers 52 of six selector levers 38 to transmit a sequential code combination. The sixth selector lever 38 is always latched at its righthand end so there will invariably be a "mark" bit transmitted at the end of the cycle.

As soon as a key lever 22 is depressed and the camshaft 58 starts to rotate, the sensing levers 30 are locked in their selected positions by the spring biased dropping of a sensing lever latching bail 142, pivoted on the post 46, and activated by a cam lobe 144 of a further cam 146 fixed on the camshaft 58. A cam follower 148 on latching bail 142 drops off the cam lobe 144, which movement causes a blade 150 at the end of latching bail 142 to drop onto the ends of the sensing levers 30. These ends have projections 152 which will take positions on one side or the other of the path of movement of latching bail blade 150 so that the sensing levers 30 are locked according to code bar position, until the latching bail lever 142 is raised near the end of one half revolution of the camshaft 58. The locking of sensing levers 30 also locks code bars 20 which in turn will prevent any other keylever 22 from being depressed before the end of one cycle.

The above described means to transmit a code is well known in the art and reference can be made to the aforementioned Patents No. 2,754,364 and 2,773,931 for various details of such a transmitter. In the prior art machines, the cam stop lever 92 is restored to its latching position by a cam fixed on the shaft 58 which operates, before the end of a cycle, to pivot the cam stop lever 92 and allow the locking lever latch surface 90 to be pivoted underneath the cam stop lever 92 by the spring 88. In the machine now being disclosed and described, a novel means to restore the cam stop lever 92 is used and is an important feature of this invention.

To stop the camshaft 58 after a code group is transmitted, the cam stop lever 92 is pivoted by the action of a restoring solenoid 102. When solenoid 102 is energized its shaft 104 and a fixed link arm assembly 106 are turned counterclockwise. Solenoid operated movement

of link arm 106, through a pivoted connection 108 with an actuating link 110, will pull link 118 to the left. The actuating link 110 turns a stop latch cam 112, on a fixed pivot post, through the cam arm 114 which causes a cam lobe 116 to engage a cam follower 118 fixed to depend from the bottom of the cam stop lever 92. Movement of the stop latch cam follower 118 forces the cam stop lever 92 to pivot about the axis of post 94 to restore its pawl 96 into the camshaft stopping position. The cam stop lever 92 is then held in this restored position by the locking lever latch 84 or by a repeat blocking lever 120 so the stop tooth 98 on the transmitter cam 100 again engages and is held from rotation by the cam stop lever 92.

When the lower end 91 of the cam stop lever 92 drops, upon movement of the locking lever latch 84 at the start of a transmission the repeat blocking lever 120, pivoted on the stud 86 and attached to the locking lever latch 84 by a spring which biases it in a counterclockwise direction, is caught in back of the cam stop lever end 91. This occurs because the repeat blocking lever 120 extends a few thousandths of an inch higher than the locking lever latch arcuate surface 90.

When the cam stop lever 92 is pivoted counterclockwise by the action of restoring solenoid 102, if the key is held down and prevents return movement of the locking lever latch 84, the repeat blocking lever 120 is pulled under the cam stop lever end 91 by the above mentioned spring. This cooperation holds the cam stop lever 92 in position to catch the tooth 98 on the transmitter cam 100 to stop rotation of the shaft 58, and avoid any inadvertent repeat transmission of a code signal.

After the key lever 22 is released, spring 88 on the locking lever latch 84 pulls the latch clockwise to its cam stop blocking position and the universal bar 80 is pushed to the left. If the key lever 22 is released earlier, that is, before the cam stop lever 92 is restored, the cam stop lever 92 becomes latched directly by the locking lever latch surface 90, rather than by the repeat blocking lever 120.

The restoring solenoid 102 is energized through the switch mechanism shown at the righthand side in Figure 3 and located at the rear of the transmitter mechanism. A cam follower 126 is pivotally supported on a shaft 128 mounted on the rear of the transmitting mechanism, and has an extension 130 upon which is mounted an insulated contact 132. The follower 126 rides the surface of a cam 134 on the rear end of the transmitting cam shaft 58 and is caused to turn clockwise as viewed in Figure 3, by the diametrically opposed cam lobes 136. When the key lever 22 is depressed, and the cam stop lever 92 is moved out of the way to allow the transmitter camshaft 58 to rotate, the cam follower 126 is on the low part of the cam 134. After the camshaft 58 has rotated a small amount, the cam follower 126 is lifted and moves the switch actuator 132 to the right to close contacts 138 completing a circuit to energize the restoring solenoid 102 (Figure 2). Thus the cam stop lever 92 is placed in position, by solenoid 102, to stop the transmitter shaft 58 well before the first half revolution of shaft 58 is completed.

It is to be understood from the foregoing description and particularly from the description of the operation of the sensing levers locking means (bail 142), which locks the code bars, that the speed at which an operator may type a message is limited by the speed of rotation of the camshaft 58, which is normally around 60 words per minute. For a skillful typist, this speed limit is an inconvenience which has been overcome under specific operational conditions by certain mechanism incorporated in this invention and which will presently be described.

TRANSMISSION OF SIMULTANEOUS CODE SIGNALS

The teletypewriter equipment, which is the subject of this invention, uses the same general form of five-unit

teletypewriter code for simultaneous operation as is used for sequential operation, an important difference being that time is not a factor. Changing the mechanical code bar setting of the keyboard to a simultaneous electrical setting is accomplished by closing electrical contacts to one circuit for a marking impulse and to a different circuit for a spacing impulse, with two circuits provided for each of the five code impulses. This is shown schematically in Figure 4.

10 To accommodate the two circuits for each of the five code impulses, an eleven-wire connection is required between the simultaneous sending unit and the simultaneous receiving unit. After the marking or spacing circuits for 15 solenoids in a receiving mechanism, to be hereinafter described.

Simultaneous signals, originating at the simultaneous transmitter mechanism of the keyboard transmitter, are received only by simultaneous receiving mechanism of the 20 perforator of the specific illustrated embodiment. This means of sending is used only when printing on and perforating tape to record messages originating at the keyboard transmitter. It is to be understood however that this invention is not limited to the specific illustrated 25 structure shown, but may be used in other forms falling within the scope of the appended claims.

Now returning to Figure 1 as a reference, the origination of the simultaneous operation takes place at the left-hand side of the keyboard transmitter. The same code bars 20, which are used to set up the sequential code, set 30 up the simultaneous code. The sequential signal is sent to a signal line and the simultaneous signal is sent to the perforator.

When a key lever 22 is depressed, each code bar is 35 shifted either to the left or to the right, depending on whether a marking or a spacing impulse is being set up. The movement of each code bar 20 pivots an associated corresponding switch arm 154 in a switch arm assembly 40 at the lefthand side of the keyboard. Each arm 154 has a circular tip 156 which engages a notch 158 provided in the lefthand upper edge of the code bar 20. There are five switch arms 154 pivoted on the frame at 160 and these switch arms operate like bell cranks with a rightwardly projecting arm 162 having a circular tip 164 which is operatively associated with a slot 166 in a sliding switch member 168. If the code group requires the first impulse to be a marking impulse, the first code bar is shifted to the right, pivoting the first switch arm 154 to the right; if the second impulse is to be a spacing impulse, the second code bar is shifted to the left, pivoting the second switch arm to the left. The other three switch arms are positioned the same way.

The bell crank action of switch arms 154 causes projections 162 to assume upward and downward positions to move and position the five associated sliding switch members 168 accordingly. Sliding switch members 168 are made from material which is electrically conductive and are insulated from the arm projection 162 by a dielectric shoe 170 disposed in slot 166. Each dielectric shoe 170 has a notch 172 to receive the circular tip 164 of switch 60 arm projection 162. Each sliding switch member 168 is biased in a counterclockwise direction, about the switch arm projection tip 164 as a pivot, by springs 173 which press the sliding contact end 174 of member 168 against associated fixed contacts which will presently be described; 65 All of the sliding switch members 168 are connected through their springs 173 to a common positive potential.

With reference now to Figures 5 and 6, further details of the simultaneous switch will be described. The five sliding switch members 168 are guided in an insulating block 180 by channels 182. This block 180 is attached to a rigid boss 184 of the machine frame by screws 186. A bracket 188 to which the springs 173 are attached is also mounted on the block 180 by screws 190, only one of which can be seen. Bracket 188, being supported by the insulating block 180, is also insulated from the machine.

Five socket connectors 192 are fixed through the block 180 on each side of the group of channels 182 and each of the socket connectors 192 has a terminal 194 projecting out of the bottom of the block, to provide two sets of five posts to which are attached the five mark and five space circuit lines. In order to complete a connection between a contact tip 174 of a sliding switch member 168 and either a mark or a space terminal 194, there is provided a plug-in switching plate 196, details of which are illustrated in Figures 6A, 6B and 6C. The plate 196 is made of insulating material and has on its top surface, Figure 6C, a printed circuit generally indicated at 198. Two side rows of plug pins 200 are fixed through plate 196, and are projected out of the bottom in an arrangement permitting plug-in cooperation with socket connectors 192. The printed circuit 198 connects the ten plug pins 200 with ten contacts 202 arranged in two parallel lines of five across the center of the plate 196, Figure 6A. The bottom ends of contacts 202 have flattened edges 204 (Figure 6A) to prevent them from turning within slots 206 formed in the bottom of plate 196, and the bottom surfaces of contacts 202 are flush with the bottom of the plate. Pins 208 (Figures 6B and 6C), of which the contacts 202 are a part, project through the plate 196 where they make electrical contact with the printed circuit 198. It can thus be seen that when circuit plate 196 is plugged into the sockets 192 (Figure 5) the two transverse rows of contacts 202 will be positioned above the two positions of the sliding switch member contact tips 174 which are pressed against one or the other of associated ones of these contacts 202 by the resilient biasing force of springs 173, as has been previously explained.

It follows then that in the marking position, the sliding contact tip 174 of a sliding switch member 168 cooperates with an upper circuit on the switch plate 196. In the spacing position the sliding contact tip 174 cooperates with a lower circuit on the switch plate 196. Thus one circuit of the simultaneous transmitter mechanism is closed for marking impulses and one circuit is closed for spacing impulses for each of the five units of the code. The eleventh line 210 is a common or return line for all ten circuits, connected to the sliding member spring bracket 188 as has been described.

After a coded group of the circuits in the simultaneous transmitter mechanism have been set up, such circuits are energized to send impulses through the five sliding switch members 168 and associated mark or space circuits to the receiving mechanism of the perforator. This is accomplished by a switch behind the keyboard which will now be described.

Referring to Figure 3, each time a code group is set up by depressing a key lever 22, the universal bar 80 moves the locking lever latch 84, which causes the cam stop lever 92 to pivot counterclockwise out of the way of stop tooth 98 of the stop cam on the transmitter cam-shaft 58. The cam stop lever 92 is non-rotatably mounted on a shaft 94 which therefore rotates whenever the lever 92 is pivoted. On the front of shaft 94, as viewed in Figure 3 (which would actually be on the rear of the keyboard transmitter frame) a switch actuating lever 212 is mounted. Switch actuating lever 212 has a pivotal connection 214 with a switch arm 216 which has a right angular portion 218 normally engaging and holding two sets of contacts 220 and 222 in open condition. Counterclockwise rotation of switch actuating lever 212 causes clockwise rotation of switch arm 216 which permits contacts 220 and 222, to become closed. Contacts 222 control the connection of a positive potential on the line 210 which is common to all sliding switch arms 168 (contacts 220 are for a purpose to be later described in conjunction with the function of the simultaneous receiver) and thus energize the simultaneous circuit. As has been described, the restoring solenoid 102 is energized before the end of each code signal transmission.

to restore the cam stop lever 92, hence the switch actuating lever 212 will rotate the switch arm 216 to permit both sets of contacts 220 and 222 to open, contacts 222 opening the simultaneous circuit.

When a message is being recorded by the reperforator receiving simultaneous signals originating at the keyboard transmitter, and the keyboard transmitter is not being used to send sequential signals to the signal line at the same time, the transmitter camshaft 58 need not rotate. To prevent the unnecessary rotation of the transmitter shaft 58 at this time, a camshaft lock solenoid 224 (Figures 3 and 16) is employed and is energized all of the time a control switch 551 (Figure 16) is in No. 1 or keyboard position. When lock solenoid 224 is energized, its shaft 226 turns clockwise, as viewed in Figure 3, and rotates an attached cam arm 228. The cam arm 228, through an abutting connection 230, rotates a lock-up lever 232 which is pivoted at 234 on the keyboard frame. A pawl end 236 of lockup lever 232 moves into the path of a lockup plate 238 on the transmitter cam-shaft 58, engages a tooth 240 of the lockup plate 238, and prevents rotation of transmitter shaft 58. It is to be understood that the tooth 240 is always in position to be engaged by the pawl 236 when the solenoid 224 is energized as this is the normal stop position of the transmitter camshaft 58.

Because of the condition, as described above, where the transmitter shaft 58 does not rotate when the keyboard is sending only simultaneous signals, it follows that pulsing of the restoring solenoid 102 by the action of the cam follower 126 on transmitter shaft 58 does not occur. But, since it is necessary to restore the cam stop lever 92 after initiation of each transmission, the restoring action is accomplished by pulsing the solenoid 102 from a switch mechanism at the perforator, as will be described.

Because the transmitter camshaft 58 does not revolve during transmission of simultaneous impulses only, such transmission can be done with a free keyboard, i.e., there is no time lag necessary between key lever depressions to allow for the half revolution of the transmitter camshaft 58 to be completed. Thus the operating speed and rhythm of the keyboard is controlled by the speed of the perforator which can be much faster than an operator normally types.

THE KEYBOARD SPACE COUNTER AND TABULATOR

Associated with the keyboard of this invention is a space counting and tabulating mechanism illustrated in Figure 15 with some specific details illustrated in Figures 2 and 16. One purpose of the mechanism is to indicate to the operator the number of characters and spaces transmitted subsequent to the preceding carriage return signal and also to indicate the character position with respect to the end of the line so that proper syllabic word breaks can be made before the end of a line is reached. It also enables an operator to transmit tabulation signal groups to page printers to facilitate typing of characters in columnar form; and to prepare perforated tape with tabulation indicia for future transmission to page printers.

In Figure 15, an indicator carriage 560 is mounted on a spirally grooved drive shaft 562 which is located and journaled in suitable bearings above the top row of keys 22. Projections inside the bore 564 of the indicator carriage 560 ride in the spiral groove 566 of shaft 562 and, as shaft 562 rotates counterclockwise, cause the indicator carriage 560 to be moved to the right. A pointer 568 mounted on carriage 560 lines up with an appropriate indicating division 570 on a calibrated scale 572 mounted above the keys in a position to be easily seen by the operator.

Grooved indicator drive shaft 562 is rotated by a ratchet pawl 574 and side face ratchet wheel 576 at the righthand end of the shaft 562. The pawl 574 is ro-

tatably mounted on a stud 578 in the end of a lever 580 and the lever 580 in turn is rotatably mounted on a post 582 fixed to the keyboard frame. Pawl 574 is held against the face of ratchet wheel 576 by a spring 584 connected between an extension arm 586 integral with the pawl 574 and a post 588 on the lever 580. The lever 580 is itself biased in a clockwise direction by a spring 590 connected between the post 588 and a spring anchor (not shown) on the machine frame. Projecting rearwardly from lever 580 is a cam follower post 592 which rides on the stop latch cam 112. The length of post 592 is greatly exaggerated in Figure 15 to enable illustration of details and its position is also shown in Figure 2. When restoring solenoid 102 is energized to restore the transmitting mechanism, as has been previously described, stop latch cam 112 is rotated about its pivot causing a cam lobe 113 to act through cam follower post 592 to raise the lever 580 which lifts the pawl 574 and turns the ratchet wheel 576 an angular distance equal to one tooth space. Indicator drive shaft 562 is thus turned and its spiral groove 566, acting on the projections inside the indicator carriage 560, will move the indicator carriage 560 to the right one character space. Pawl 574 releases the ratchet tooth on its return or downward stroke (caused by counter-clockwise rotation of the cam 112 when the solenoid 102 is de-energized).

As shaft 562 is turned counter-clockwise to index the counter, a clock type coil spring 594, at the left end of the shaft, is wound up. This spring 594 has the inner end 596 attached to the shaft 562 and its outer end attached to a post 598 on the frame. To prevent clockwise rotation of shaft 562 while pawl 574 is being returned or lowered to the next tooth engaging position, a ratchet wheel detent 600, mounted on a fixed post 602, is biased against the ratchet wheel 576 by a spring 604. Each time the ratchet is rotated a tooth space, detent 600 is cammed out of engagement behind a ratchet tooth and then pulled back behind the next tooth by spring 604. The winding of the clocktype coil spring 594 stores the power required to return the indicator carriage 560 to its start of line position when a carriage return key 606 is depressed.

In order to free the ratchet 576 to allow spring 594 to rotate shaft 562 clockwise for carriage return, both the ratchet pawl 574 and the ratchet detent 600 must be moved out of engagement with the ratchet wheel teeth. This is accomplished as follows: A transverse carriage return bar 608, slidably mounted above the key levers on posts 610 and 612, has a depending leg 614 disposed adjacent the carriage return key lever 616. The end of leg 614 is formed as a foot 618 with an angular side 620 which is engaged by the key lever 616, whenever the carriage return key 606 is depressed, causing the carriage return bar 608 to be cammed to the right. An upwardly extending finger 622 on the lefthand end of carriage return bar 608 engages the left side of the ratchet detent 600 and rotates the detent out of engagement with the ratchet wheel 576. Located in parallel arrangement behind the carriage return bar 608 is a function blocking bar 624 urged to the left by a spring 625, also slidably mounted on posts 610 and 612, and operatively connected to the carriage return bar 608 by a post 626, fixed in the carriage return bar 608 and projecting into an elongate opening 630 in the function blocking bar 624. Function blocking bar 624 also has an upwardly extending finger 632 which is adapted to engage the left side of the ratchet pawl 574. When carriage return bar 608 is moved to the right, post 626 engages the end of opening 630 and shifts the function blocking bar 624 to the right, whereby upstanding finger 632 moves the ratchet pawl 574 out of engagement with the ratchet wheel 576. Thus, with both the pawl 574 and the detent 600 disengaged from the ratchet wheel 576, the grooved

indicator shaft 562 will rotate clockwise under power of coil spring 594 to return the indicator carriage 560 to the start of the line.

It will be noted that the carriage return bar 608 has a notch 634 in the top edge at its lefthand end, which notch is engaged by a detent 636 when the bar 608 has been moved to its righthand position. The detent 636 is on one arm of a two-armed lever 644 mounted on pivot 638 and is biased clockwise by a spring 640 connected to an upwardly projecting arm 642. When the carriage return key 606 is manipulated, the carriage return bar 608 will always be latched in its righthand position so that releasing of the carriage return key before completion of the return of the indicator carriage 560 will not allow the pawl 574 and detent 600 to stop its return to the start of the line. When the indicator carriage 560 reaches its start of line position the carriage body will strike the end 646 of the upper lever arm 642 and rotate the latch lever 644 counter-clockwise to unlatch the bar 608. The top end 646 of the lever arm 642 will be swung far enough to the left to be struck by a pin 648 fixed in the shaft 562 which stops rotation of the grooved shaft 562 and stops the return movement of indicator carriage 560 at the exact start of line position.

As spacing is not desirable for certain key operated functions, the coded transmission of which is necessary when the message is transmitted to a page printer, the indicator carriage spacing function must be disabled during manipulation of these certain keys. The function blocking bar 624, described above, serves this purpose by the provision of depending legs 650, one for each of the function keys, e.g., Letters, Figures and Line Feed. These depending legs 650 are identical to the leg 614 on the carriage return bar 608 and whenever one of the above mentioned function keys is depressed, the function bar 624 will be cammed to the right to cause the upstanding finger 632 to engage and rotate the ratchet pawl 574 to the right and away from the ratchet wheel 576 so when the arm 580 and ratchet pawl 574 make their upstroke during the transmission of the code group signal for the function, grooved shaft 562 will not be rotated and the indicator 568 will not be indexed.

A repeat key is provided in this invention to facilitate the transmission of repeated characters and is described and operates in the following manner: The key with part of its mechanism may be seen at the righthand portion of the keyboard of Figure 15 and additional mechanism is illustrated in Figure 2. It is to be understood that manipulation of the repeat key does not itself transmit any signal and is only effective when used with another key. The repeat key lever 652 has a bridge portion 654 to span the universal bar 80 and the five code bars 20, thus its manipulation will have no effect upon these bars. At the rear of the code bars 20, a bell crank lever 656 is rotatably mounted on a post 658 fixed in the keyboard frame and has a depending leg 660 angularly disposed under the key lever 652. Locking now at Figure 2, righthand arm 659 of bell crank lever 656 extends under a lefthand extension 661 of the repeat blocking latch 120. The repeat blocking latch 120 is biased counter-clockwise by its spring 121 and the biasing force of this spring also acts through extension 661 to press the angular end 660 of the bell crank lever 656 against the bottom of the repeat key lever 652.

When the repeat key is depressed, the angular end 660 of bell crank lever 656 will be cammed to the right and its righthand arm 659 will be raised to rotate the repeat blocking latch 120 to an unblocking position. In this position the arm 92, which starts the sequential signal transmission and stops the sequential signal at the end of a cycle, will not be restored to and held in stopping position so long as the universal bar 80 is in its righthand position. It follows then that, when any character or function key is manipulated along with the repeat key, the sequential code signals for that character or function

will be repeated until either that key or the repeat key is released; this is a necessary feature of the tabulating mechanism which will now be disclosed.

THE KEYBOARD TABULATOR

Again referring to Figure 15, a tab structure 664 is mounted at the top of the keyboard over the character and space indicating scale 572. This tab structure 664 includes a shaft 666 journaled at its ends in the keyboard frame and rotatably carrying in juxtaposition a plurality of tab stop levers 668, one above each division of the aforementioned indicating scale 572. Each tab stop lever 668 consists of a finger tab 670, a projecting stop 672, two detent notches 674 and 676 and a central aperture 678 through which passes the shaft 666. The tab stop levers 668 are mounted to rotate freely upon the shaft 666 and are held in unselected and selected positions by associated leaf spring tines 680, pressing in notch 674 or notch 676. An integral part of the tab structure 664 is a channel member 682 extending the full length of the tab structure and having projected ends 684 bent at right angles and containing bearing holes 686 in each end 684, permitting the channel member 682 to be rotatably mounted upon shaft 666. In the front and back sides of the channel 682 are a plurality of slots 688 equal in number and spacing to the levers 668. The finger tabs 670 and stops 672 of levers 668 project through the front slots 688 and the portions of levers 668 having the detent notches 674 and 676 project through the slots 688 at the back of the channel. The side edges of front and rear slots 688 will coact with the tab stop levers 668 to maintain the levers perpendicular to the axis of the shaft 666 and in correct relation to the index positions of the scale 572. A spring plate 690, with a plurality of depending spring tines 680 equal in number and spacing to the levers 668 is attached to the top of the channel member 682 and its tines 680 mate with the detent notches 674 or 676 of the tab stop levers 668. The tabulating structure 664 including the shaft 666, stop levers 668, channel member 682, etc., can rotate as a unit with respect to the keyboard frame for a purpose which will presently become apparent.

Near the left end of the tab structure 664, and rotatably mounted upon shaft 666, is a two-armed lever 692, its upper arm 694 positioned to abut a shoulder 696 of channel member 682 and its lower arm 698 projecting forward into a slot 700 in the end of an operating lever 702. The arm 694 of lever 692 is held against the channel member shoulder 696 by the force of a spring 704 connected between the end of the arm 694 and an integral projection 706 of channel 682.

Rotation of operating lever 702, which will cause tab structure 664 to be rotated, is accomplished by rotation of a shaft 708 to which operating lever 702 is secured. Another lever arm 710 is also rigidly secured to shaft 708 and has its end operatively connected to a tabulator bar 712 by being disposed in a notch 714, provided in the tabulator bar. The tabulator bar 712 is slidably mounted on the keyboard frame in front of universal bar 80 and is biased to the left by a spring 716 connected between a post 718 in bar 712 and the keyboard frame. This tabulator bar 712 has a cutaway section 720 normally disposed under all of the key levers, except the repeat key lever 652, so that any one of them can be depressed without striking the bar 712. An angular side edge 722 of the tabulator bar cutaway section 720 is directly underneath the repeat key lever 652 so that depression of that lever will engage the angled edge 722 and cam the tabulator bar 712 to the right.

Mounted in fixed relation upon the top of the indicator carriage 560 is an upstanding cylinder 726 within which is a post 728, freely disposed to turn within the cylinder and having its upper end projected from the cylinder. On top of post 728, and fixed to rotate with it, is a plate 730 of dielectric material. A spiral spring 732 surrounds

post 728, has one end attached to the plate 730 and the other end attached to a spring post 734 fixed in the indicator carriage. Attached on the top of dielectric plate 730 is an upright bracket 736 positioned so its path of movement during carriage translation causes it to engage any operatively projected stop 672 of selected ones of the tab stop levers 668. The bracket 736 is mounted on plate 730 forward of the pivot axis of post 728 and, when a stop 672 of a selected tab stop lever is struck by bracket 10 736, as the indicator carriage 560 moves to the right, the dielectric plate 730 and attached post 728 will be rotated clockwise in cylinder 726 against the force of the spiral spring 732. Mounted on the portion of dielectric plate 730, and thus electrically isolated from the machine frame, 15 is an electrical contact plate 738 having two integral spring finger contacts 740 and 742, i.e., bridging contacts. Directly behind this two finger contact structure are two electrically conductive, transverse bars 744 and 746, insulated from each other, and from the machine 20 frame, and connected in series with a line 748 and across the contacts 138 to the restoring solenoid 102 (see also Figure 16). Note, the normal position of dielectric plate 738 against an indicator carriage stop lug, as dictated by the biasing force of connecting spiral spring 732, will 25 maintain the two finger bridging contacts 740 and 742 away from engagement with the conductive bars 744 and 746. However, if at any position of the indicating carriage 560, the bracket 736 on the dielectric plate 730 engages a selected tab stop 672, the plate 738 will rotate 30 against spring bias so the two bridging fingers 740 and 742 engage and bridge respective conductive bars 744 and 746.

Having described the mechanical structure of the character indicating and tabulating mechanism, its operation 35 and use will now be explained.

If, for example, an operator of this equipment wishes to transmit certain characters of a message which are to be in columnar form indented from the lefthand margin by thirteen character divisions, the thirteenth tab stop lever 668 is pulled down (Figure 15), the indicating pointer 568 being at zero position. In the normal position of the tab structure 664, a selected tab stop 672 will be disposed above and will be cleared by the bracket 736 on the dielectric plate 730 carried by the indicator carriage 560, but when the operator presses the repeat key 40 lever 652 the whole tab structure 664 will turn counterclockwise through the operation of the linkage train from the rightwardly moving tabulator bar 712, operating lever finger 710, counterclockwise rotation of the levers 702 and 692, and the pull of spring 704. The selected tab stop 672 is thus moved into the path of the bracket 736.

Following the pressing and holding of the repeat key lever 652, the space bar 750 is depressed which moves universal bar 80 to the right and starts transmission without repeat blocking. Space signals will be repeated and the indicator carriage 560 will move to the right until the thirteenth position is reached. As carriage 560 moves into the thirteenth position the bracket 736 on dielectric plate 730 will strike the selected tab stop 672 and the 45 spring finger contacts 740 and 742 will be rotated up against the contact bars 744 and 746 to close a circuit from the battery to the restoring solenoid 102. The indicator shaft 562 was incrementally rotated to move the carriage 560 to the thirteenth position by reason of 50 the energization and deenergization of the restoring solenoid 102 each time the transmitter camshaft cycled to close and open contacts 138, but at the thirteenth position the closing of the tabulator circuit across conductive bars 744 and 746 will hold the solenoid 102 in energized con- 55 dition and the transmitter cam stop lever 92 will be held in its stop position to prevent further repetition of space signals. Repeat transmission will thus cease at the thirteenth position as dictated by selected tab stop 672.

The repeat key is then released by the operator permitting the tabulator bar 712 to be pulled to the left by

its spring 716. Lever 692 rotates the tab structure 664 clockwise, releasing the dielectric plate bracket 736 and the finger contacts 740 and 742 will move away from conductive bars 744 and 746 to open the circuit. The solenoid 102 will thus be de-energized and the keyboard and transmitter will be in normal position ready for start of the next signal transmission.

Subsequent signal are transmitted in the normal manner and when the carriage return key is depressed the indicator carriage 560 will return to the start of the line without interfering with the tab stop structure, where, after a line feed signal, the above process is repeated so long as tabular settings are desired.

Should the operator wish to type any line without tabulation but wish to retain the tab stops in their selected positions, the tab structure 664 can be latched in its upper position. This is accomplished through the use of a latch lever 754 pivotally mounted at the left of the keyboard. Lever 754 has a latch end 756 to engage a notch 758 in the end 684 of the channel member 682. A manual control arm 760 on lever 754 projects forwardly and latch lever 754 is retained in either its latching or unlatched positions by a spring detent 762 coacting with detent notches 764 in the latch lever. When lever 754 is rotated clockwise to engage channel member notch 758 the tab structure 664 cannot turn counter-clockwise with lever 692, instead, the spring 704 will be stretched whenever the repeat key is operated; other than that the keyboard will operate in a normal manner.

It is to be understood that any number of tab stops may be selected for the transmission of signals to create a plurality of columns, but the selected stops will be rendered operative only when the repeat key is employed. Any character signal may be repeated to cause the indicator carriage to move up to the tab stop position; function signals will not move the indicator carriage as hereinbefore explained, so they cannot be used to tabulate even though such signals would be automatically repeated, when the repeat key is employed.

Carriage return signals cannot be automatically repeated due to the presence of the following blocking structure: Located on the tabulator bar 712 directly to the left of the carriage return key lever 616 is a stop 768 which is moved to a position underneath the carriage return key lever 616 when the repeat key is operated thus preventing manipulation of the carriage return key. This feature is desirable to prevent possible damage or at least to insure uninterrupted operation of the indicating mechanism under the following unusual condition: When several tabs are being used and the indicator carriage has passed the first set tab and characters are being repeated toward the next tab, and inadvertent depression of the carriage return key, if such depression were possible, would cause the indicator carriage to return to a start of line position and the contact structure would strike the tab stop in the wrong direction with damage to the contact structure or tab stop. The indicator carriage under such conditions might be stopped at the tab stop position while the page printer, which would be typing the transmitted message, would be at the start of the line and the two machines would no longer be in synchronization so far as character position is concerned.

Having thus described a type of transmitter, with indicating and tabulating mechanism, for sending either sequential or simultaneous or both types of telegraph signals concurrently, a receiving mechanism for such sequential and simultaneous signals will now be disclosed.

RECEIVING MECHANISM (REPERFORATOR)

The receiver of this particular embodiment is known in the art as a reperforator. It will receive a telegraph message from a wire and translate the code to type the message on a paper tape and at the same time record the code in the tape by means of punched holes. A reperfo-

rator of the nature referred to is disclosed in United States application Serial No. 472,076, filed November 30, 1954, to which reference may be made for details of type-wheel, printing and perforating mechanism not illustrated herein. In order to mechanically utilize the electrical form of the received code signals the elements of the code must be converted into mechanical settings. U.S. Patent No. 2,754,361 discloses a selector for this purpose, components of which are employed as subcomponents in the specific receiver embodiment of this invention. A very brief description of the sequential selector of this device, and its operation will now be given.

All of the receiving selector mechanism, both sequential and simultaneous, is located at one side of the reperforator and the essential elements are shown in Figures 9 and 11. To receive sequential signals, to be converted to mechanical settings, there is a selector magnet 244 with a movable armature 246. The winding selector of magnet 244 receives the sequential electrical pulses of the code combination and the armature is caused to move to one of two positions, depending on whether the impulse received is a marking or a spacing impulse. Each of the five electrical impulses that comprise any code combination group is recorded in the form of clockwise or counterclockwise movement of five corresponding Y-levers 248. This is accomplished through the use of five selector cam lobes 250 operating in conjunction with five selector levers 252 and the armature 246. The five Y-levers 248 are mounted on a common pivot stud 254, the five selector levers 252 are mounted on a pivot stud 256 and the five selector cam lobes 250 are mounted in axially spaced relation on a rotatable camshaft 258 with the cam lobes projecting at progressively offset angles from the camshaft 258. One selector cam lobe 250 operates in conjunction with only one associated selector lever 252 and that lever with only one associated Y-lever 248. Thus there are five planes, one in back of the other, each containing a set of these three parts. The end 260 of the selector magnet armature 246 is broad enough to engage all five selector levers. Each of these five sets of parts records one of the impulses of the five unit code. The first set records the first impulse, the second set the second impulse, etc.

During the time a marking impulse is received, the selector magnet armature blade 260 is moved into the path of a selector lever 252. Near the middle of this time period, the selector cam lobe 250 corresponding to the impulse being received will be rotating, will engage and raise the selector lever 252. As the armature blade 260, being positioned in the path of a selector lever 252, prevents raising of the right end of the selector lever, the selector lever is forced to rise at its left end by sliding on the bearing shoe 262. In so doing, the selector lever 252 pushes against the Y-lever 248 at its end 264, turning the Y-lever clockwise (unless it is already in that position). Further rotation of the selector camshaft 258 permits the selector lever 252 to drop back, but the Y-lever 248 is held in the clockwise position by a detent 266. A marking impulse is thus recorded in the form of the clockwise position of a Y-lever.

During the time a spacing impulse is received, the selector magnet armature blade 260 is moved away from the selector levers 252. Near the middle of this time period, the rotating selector cam lobe 250 corresponding to the impulse being received will engage and raise the corresponding selector lever 252. The end 260 of the armature does not obstruct the righthand end of the selector lever 252, therefore the righthand end is free to rise. In rising, the righthand end of the selector lever 252 pushes up against the end 268 of the Y-lever 248, turning the Y-lever counterclockwise (unless it is already in that position). A spacing impulse is thus recorded in the form of the counterclockwise position of a Y-lever. The Y-lever detent 266 also holds the Y-lever in the space position.

To synchronize the selector cam lobes 250 with the incoming electrical impulses, cam lobes 250 are set into motion from a stopped position at the start of each code group and stopped at the end of each code group. The selector camshaft 258 is driven by a drive shaft 270 through a friction clutch 272. Normally when no messages are being received, current flows in the windings of the selector magnet 244 and the camshaft 258 is prevented from turning by the interoperation of the selector magnet armature blade end 260, stop lever 274, and a camshaft stop plate 276. When moved to the left, the armature blade end 260 engages the stop lever 274 which in turn prevents the stop plate 276, and selector camshaft 258, from turning. When the start (no-current) impulse for a code group is received, the armature end 260 is moved to disengage the stop lever 274, releasing it and the stop plate 276; the selector camshaft 258 immediately starts to rotate, bringing the first selector cam lobe 250 into engagement with its selector lever 252 by the time the next impulse of the code group (first bit) is received.

Thereafter each of the remaining five selector cam lobes strikes its respective selector lever when the corresponding code bit is being received. All five cam lobes operate their selector levers within one-half revolution of the camshaft. The camshaft is limited to making only one-half revolution per code group because, after the last five bit impulses are received, the stop impulse moves the magnet armature 246 to the left to engage the stop lever 274. The other end of the stop plate 276, which then comes around, engages and is held by the stop lever 274 to stop the camshaft 258. If further details of the sequential receiving structure is desired reference is made to U.S. Patent No. 2,754,361.

TRANSFER FROM SEQUENTIAL TO SIMULTANEOUS

Five dielectric code plates 280 of a code actuated switch must be positioned according to the incoming sequential code group in order to convert the sequential form of the code group to a simultaneous form to be received by five solenoids for subsequent conversion to printed and punched tape. The incoming code group as stored in the Y-levers 248, by clockwise and counter-clockwise settings, is transferred to the code plates 280 by mechanism to be now described.

Each code plate 280, at its lower end, carries a slotted metallic shoe 282 which mates with a corresponding tail 284 of one of five T-levers 286 all of which are mounted on a common pivot 288 carried on the end of a transfer lever 290. The five code plates 280 are mounted for reciprocation on two fixed posts 283 and 285 which pass through appropriate slots in the code plates. Turning a T-lever 286 on its pivot will cause its mating code plate 280 to move up or down. The T-levers are mounted in the same planes as their corresponding Y-levers, and movement of the transfer lever 290 engages certain ones of the ends of the T-levers 286 with certain ones of the ends of the Y-levers 248. The ends 292 and 294 of the arms of T-levers 286 are spaced farther apart than associated ends 296 and 298 of Y-levers 248, therefore only one end of the T-lever can engage one end of a Y-lever at any time and the ends which engage will depend upon Y-lever position. When the transfer operation takes place, the transfer lever 290 moves all of the T-levers against the Y-levers and the T-levers assume positions corresponding to associated Y-levers thus transferring the five stored codes settings of the Y-levers to the T-levers and thus to the code plates 280.

The transfer operation, a reciprocatory swinging movement of the transfer lever 290, takes place after the fifth code bit is stored in the Y-levers but before the selector camshaft 258 is brought to rest by the stop signal. A sixth or transfer lever latch tripping cam 300, Figure 11, mounted on the selector camshaft 258, trips a transfer

lever trip latch 302 which holds transfer lever 290 in a lefthand position, and the transfer lever 290 is pulled clockwise by the transfer lever spring 304. The timing of the latch tripping cam 300 with respect to the five selector cams 250 and stop plate 274 is such that the tripping action takes place only after the Y-lever selecting operation is completed and before the selector camshaft 258 is stopped.

Each of the five code plates 280 is associated with one of five contact wipers 308, each of which is disposed in a cut-out 310 in the upper end of one code plate. With reference to Figures 7 and 8 for details, these contact wipers 308 are square in cross section and are bent in the shape of a W with the two ends 312 and 314 forming the wipers and the middle U-section 316 forming an anchor clip for a biasing spring 318. Each wiper 308 (Figure 7) slides within slot 320 of a guide block 322, one slot being provided for each wiper. Guide block 322 is fastened to a switch plate 324 by screws 326. The width of block 322 (Figure 7) is narrower than the cut-outs 310 in the ends of code plates 280 to permit unobstructed movement of the code plates when they slide into "mark" and "space" positions. Biasing springs 318, one for each wiper 308, pass through an opening 328 in switch plate 324, through a hole 330 in a backing block 332 and are attached to an anchor bar 334 located at the rear of the hole 330.

The printed circuit switch plate 324, Figure 10, has two contact strips 336 and 338, disposed adjacent opposite side edges of opening 328, which provide the common contacts of the simultaneous circuit. These common contact strips 336 and 338 are connected and terminate at a pin 340. The arm 312 of the wiper 308 is associated with the common strip 336 and the arm 314 is associated with the common strip 338 and one or the other of the wiper arms 312, 314 always rests on one or the other of the common strips when the wiper 308 is in spacing or marking position. The printed switch plate 324 also provides two more contacts for each contact wiper, one (342) above the strip 336 and one (344) below the strip 338. These contacts have printed circuits which terminate at pins 346a, b, c, d and e, and 348a, b, c, and e. Thus when a code plate 280 is in the upper position (spacing), the lower arm 314 of the wiper 308 rides against the lower common contact strip 338 while the upper arm 312 rides against its associated contact 342, closing one circuit to the simultaneous selecting mechanism. In this manner, each code plate 280 closes one circuit, if the impulse it represents is a marking impulse, or closes a different circuit if the impulse it represents is a spacing impulse.

A code actuated switch function shaft 350, Figures 9 and 11 performs three main functions: (1) It restores the transfer lever 290 and mechanism to its latched position; (2) it provides power to register and lock the code plates 280 in place and (3) it controls a switch which energizes the circuits of the simultaneous receiving mechanism, to be later described.

Function shaft 350 is driven in a counterclockwise direction through a toothed clutch 352 at the righthand end of the shaft. Shown in Figure 11, a spur gear 354, carrying one part of clutch 352, is in constant rotation through its engagement with a driving gear 356 on the power shaft 270. The clutch 352 is engaged when the transfer operation takes place and is accomplished by the clockwise turning of clutch latch 358 which, through a shaft 360, is connected to the transfer lever 290 and is rotated when the transfer lever latch 302 is actuated to release the transfer lever. Turning of clutch latch 358 permits the clutch members to spring together and function shaft 350 starts to rotate. The T-levers 286 must be moved away from the Y-levers before the next code group can be set up in the Y-levers and this action is accomplished when the transfer lever 290 is restored to the latched position. The transfer lever 290 must be rotated slightly counterclock-

wise against the tension of the spring 366 and latched in this position by the transfer lever latch 302. A cam 362 at the lefthand end of the function shaft 350 operating on a roller 364, mounted on an extension arm of transfer lever 290, accomplishes this restoring action during a one-half revolution of the shaft 350 by camming the transfer lever 290 toward the restored position. Near the end of the one-half revolution, as the transfer lever moves into restored position, the transfer lever latch spring 366 pulls the transfer lever latch 302 into position to latch the transfer lever.

After the five code bits have been received by the sequential receiver, and the associated selector mechanism has caused the positioning of the five code plates 280, the plates 280 are registered and locked in place to align the contact wipers 308 in their exact correct selected positions. As illustrated in Figure 11, this function is performed by the interoperation of a cam 368 on the function shaft 350, a cam follower 370 on an extension of a registering lever 372, pivoted at 374, and having a registering bail 376 on a second extension. Registering lever 372 is biased clockwise by a spring 377. While the selection and transfer operations are taking place, the cam follower 370 rests on the high portion of the cam 368. The function shaft 350 is stationary during this time so the cam 368 is not rotating. When function shaft 350 is coupled to the drive gear 354 through clutch 352, so shaft 350 starts to rotate, the cam follower 370 drops off of the high portion of the cam 368 and the bail 376 moves up against notches 378 of the plates 280. The notches 378 are aligned, with the upper notches of the mark positioned code plates in line with the lower notches of the space positioned code plates, so that the five notches are simultaneously engaged by the bail 376 of the lever 372. The notches 378 are V-shaped, and the bail 376 has a knife edge, hence slightly out-of-line code plates are cammed into place as the register bail 376 engages the notches.

To prevent arcing at the contacts of switch plate 324 when wipers 308 slide into their selected positions, the electric circuit to the common input of plate 324, which is received at the pin 340, is held in open condition. After the bail 376 positions and locks the plates 280, the simultaneous circuit is pulsed. A cam 380 on the function shaft 350 is associated with a pair of contacts 382 in series with the energizing circuit to the simultaneous receiving mechanism, and when the lobe of cam 380 strikes the contacts 382 they will be closed to pulse the simultaneous code plate circuit.

SIMULTANEOUS RECEIVER

Five solenoids arranged in a unitary assembly are employed to operate the simultaneous receiving mechanism of this invention and by this arrangement a set of five Y-levers are positioned simultaneously instead of sequentially as in the above described sequential receiver. Having general reference to Figures 9 and 11 and specific reference to Figure 12, an iron housing 386 contains the solenoids. Housing 386 is an assembly of two blocks, an upper block 388 and a lower block 390, fastened together by screws 392 through flanges 394 on the two blocks. Each of the blocks 388 and 390 has five vertical chambers, 396a, b, c, d and e, in the upper block, and 398a, b, c, d, and e in the lower block, to receive solenoid coils 406 (upper) and 408 (lower). The corresponding upper and lower chambers 396 and 398 are aligned and arrayed in the manner illustrated in Figure 13 wherein in the vertical axes of the chambers 396, 398 are spaced apart, from front to back, a distance equal to the spacing of a group of Y-lever setting elements 452 which are disposed directly below the solenoid housing 386. The spacing of the axes of the chambers 396, 398 in the other direction places two of them, the axes of chambers 396b and 396d, on the right of the center line of the housing 388 and three of them, the axes of chambers 396a, 396c and 396e, on the left of the centerline. Upper and lower

chambers 396 and 398 are bored from the abutting ends of the blocks 388 and 390 and terminate a short distance from the outside ends of the blocks. Smaller coaxial threaded holes 400 and 402 connect the ends of the respective chambers 396 and 398 to the outside ends of the housing 386.

Sandwiched and clamped between the two blocks 388 and 390 is an iron or mild steel plate 404 with holes drilled in it to align with the associated chambers 396, 398 of the housing 386. These holes are slightly smaller in diameter than the chambers 396, 398, providing a slight shoulder at the inner end of each chamber portion 396 and 398, for a reason which will presently become apparent.

The assembled receiver solenoid unit contains the following elements within each chamber as illustrated by the cross-sectional view of the one chamber seen in Figure 12. Two solenoid coils 406 and 408, wound on sleeve cores 409, made of insulating material, are held snugly between the ends of the respective upper and lower portions 396 and 398 of each solenoid chamber and the aforementioned shoulder, provided by the mid-plate 404, by spring washers 410 and 412. Passing through the sleeve cores 409 of the coils 406 and 408 and through the associated hole in the mid-plate 404 is a non-ferrous metallic sleeve 414 within which an iron or mild steel plunger 416 is disposed with a freely slidable fit. Each plunger 416 has conical ends 418 and 419 and its lower end 419 has an axial bore within which the end of a wire 420 is press fitted. Plungers 416 are free to independently move up and down within the cylinders 414 and are limited in their travel by steel end plugs 422 and 424. Plugs 422 and 424 are identical except for a bore through the axis of each of the lower plugs 424 through which the aforementioned wires 420 project. Each of plugs 422 and 424 have a threaded portion 426 to mate with the threaded holes 400 and 402 at the end of the upper and lower cylinders, and a smaller inner cylindrical end 428. The inner ends 428 of upper plugs 422 have conical recesses 430 to mate with the conical plunger tips 418 and the ends 428 of lower plugs 424 have a frusto-conical recess 431 to mate with the lower tips 419 of plungers 416. Each plug 422 and 424 has an outer hexagonal head 432, for tool engagement, and each has a lock nut 434 threaded on its threaded portion 426. Plugs 422 and 424 are turned into the holes 400 and 402 a distance which will allow between $\frac{1}{32}$ inch to $\frac{1}{16}$ inch longitudinal movement of the associated plungers 416 within cylinders 414. The reason for variations in plunger movement will be later described. When the proper amount of movement of each plunger has been set, the lock nuts 434 are turned down against the housing 386 to secure the plugs.

Centrally located in upper block 388 is a longitudinal through bore 436 aligned with a centrally located hole (not shown) in the plate 404. Channels 440 and 442 (Figure 12) in the inside faces of the blocks 388 and 390 (also shown dotted in Figure 13) connect each solenoid chamber with the central bore 436. In the assembled solenoid block these channels provide passages to enable the wires from the solenoid coils 406 and 408 to be led through the central bore 436 to outside connections.

Magnetic detent of the solenoid plungers will be described with reference to a schematic magnetic circuit of the above described solenoid group shown in Figure 14. The plunger 416 is illustrated in its lower position which is the "space" position for this particular solenoid. The lower convex conical tip 419 of the plunger is held against the concave conical end 431 of the lower plug 424 due to magnetization of the steel plug 424. The polarization of this magnetized plug 424, as shown, is with the south pole at the top and is due to residual magnetism from a previous "space" pulse to the illustrated lower coil 408. The flux lines due to this permanent magnet (plug 424) are shown by the light dotted lines indicated by the number 444. As may be seen, most of this flux flows

through the mid-plate 404 to complete the circuit, but some of the flux flows up the blocks 390, 388, through the top plug 422, across the air gap 446 and back down through the plunger 416. This latter flux is indicated by the numeral 448. As shown by this diagram, the plunger 416 will be permanently held against the lower plug 424. There is a slight attractive force between the upper tip 418 of the plunger 416 and the end 430 of the upper plug 422, but as there is a large air gap at the upper end, the attraction is slight and can be ignored.

When the "mark" coil 406, at the top of the solenoid, is pulsed, as was explained earlier, there is a magnetic flux circuit caused to flow as indicated by the heavy dotted lines 450 at the left side of the diagram. Due to the direction of the current pulse in this top coil 406, the upper tip 418 of the plunger 416 will become a north pole and the lower tip 419 will become a south pole. As the end 431 of the lower plug 424 is also a south pole, the two poles will repel one another to release the plunger 416 from the magnetic locking effect of bottom magnetized plug 424. At the same instant that the lower plug 424 releases the plunger, the magnetic field created by flow of current in the coil 406 causes the plunger 416 to tend to center itself in the upper coil 406 and it is snapped up into "mark" position with its upper tip 418 against the conical end 430 of the top plug 422.

The polarity of upper plug 422 is changed by the magnetic flux created by the current flowing in the top coil 406 and its conical end 430 thus becomes a south pole to attract and magnetically hold the plunger in this upper position. Due to the fact that the end plugs 422 and 424 are of highly magnetically retentive material, they are slower to respond to changes in polarity than is the magnetic flux circuit and always lag behind. Because of this feature when the current flows through the windings of the coil 406, the flux indicated at 451, which causes the lower plunger tip 419 to become a south pole and also causes the end 431 of the bottom plug to become a north pole, the lag mentioned above enables the two parts 419 and 431 to be repelled before the end 431 of lower plug 424 has its polarity changed.

Thus there has been disclosed and described a solenoid plunger which may be driven one way or the other by alternately energized coils 406 and 408 and which will always be magnetically locked in its set position when the coils are de-energized.

Referring now to Figure 12, directly beneath the simultaneous solenoid receiver assembly described above, are a group of five Y-shaped levers 452, pivoted on a post 454 and having a slight turning motion one way or the other which is limited by a stop post 456, coacting with the sides of a slot 458 in each Y-lever. The stop post 456 is directly over the Y-levers pivot post 454 and the slots 458 are slightly wider than the diameter of the stop post 456. Clockwise rotation of a Y-lever is a result of a "mark" signal and counterclockwise rotation of a Y-lever is a result of a "space" signal. These five Y-levers 452 are somewhat similar in appearance to the five Y-levers 248 of the sequential receiver and serve the same purpose. Each Y-lever 452 has three arms, a righthand arm 460 and two lefthand arms 462 and 464. Movement of the Y-levers 452 is effected through their attachment to associated ones of the solenoid plunger wires 420 projecting through the bottom of the simultaneous receiver housing 386. The front Y-lever has a wire 420a attached to a post 466 at the left of the pivot 454 and is associated with the first element or bit of the Baudot code. The second Y-lever has the wire 420b attached to a post at the right of the pivot and is associated with the second element of the code. The third Y-lever has the wire 420c attached at the left of the pivot 454 and away from the pivot a distance double that of the first wire. The fourth Y-lever has the wire 420d attached at the right of the pivot and away from the pivot a distance double that of the wire 420b. And the fifth Y-lever has

its wire 420e attached to the left of the pivot and directly behind the post 466 on the first Y-lever. The plungers associated with wires 420a, 420c and 420e move down when their "mark" solenoids are pulsed and up when their "space" solenoids are pulsed. The plungers associated with wires 420b and 420d move up when their "mark" solenoids are pulsed and down when their "space" solenoids are pulsed.

With the described arrangement of the wire connections to the Y-levers, it is necessary that the solenoid plungers 416c and 416d, within the solenoid receiver housing 386, move twice as far to set the third and fourth Y-levers as to set the first, second and fifth levers due to the greater distance of the wire attachment from the pivot 454. This difference in movement of the plungers 416 is adjusted by the screw plugs 422 and 424 as was previously explained. The forces necessary to turn the Y-levers are about equal regardless of the greater movement of two of the plungers due to the fact that the two that have to move the farthest are also farther from the pivot 454 so that a greater lever action is available for the turning of these latter two levers.

Referring now to Figure 11, the operations of the simultaneous receiving and translating mechanism subsequent to positioning of Y-levers 452 will now be described:

When the five "mark" or "space" circuits set up by code plates 280 are pulsed by the pulsing cam 380 on the function shaft 350, associated "mark" or "space" solenoids 30 within the solenoid receiver housing 386 are energized and magnetically locked to simultaneously move the five Y-levers 452 to desired clockwise or counterclockwise positions; clockwise for marking impulses and counterclockwise for spacing impulses. A second transfer lever 35 468, for transferring settings of Y-levers 452, is fixed on the end of a shaft 470 and, with shaft 470 can turn clockwise a slight amount under the biasing force of a spring 472. This transfer lever 468 is latched in cocked condition against the force of spring 472. Release of transfer 40 lever 468 is accomplished by energizing an electromagnet 474 which attracts a latching armature 476 pivoted at 478 and biased away from the magnet 474 by a spring 480. The armature 476 has a latching end 482 which engages an end 484 of a latch lever 486 fixed to the second transfer lever shaft 470. When the magnet 474 is energized, 45 the armature 476 pulls up and releases the latch lever 486 which in turn permits the transfer lever 468 at the other end of the shaft 470 to turn under bias of spring 480.

Mounted on the end of an arm 473 of the second transfer lever 468 is a post 488 which pivotally mounts five 50 T-levers 490, identical to the T-levers 286 previously described for the sequential receiver. When transfer lever 468 is released the T-levers 490 are moved forward against the simultaneously positioned Y-levers 452 and one or the other of the arms 492 or 494 of the T-levers 490 will strike 55 one or the other of the arms 462 or 464 of the Y-levers 452 to turn the T-levers in clockwise or counterclockwise directions. Clockwise rotation of a T-lever is the result of a "space" signal and counterclockwise rotation is the result of a "mark" signal.

The "start" or latch electromagnet 474, which releases the second transfer lever 468 as described above, is controlled through contacts 496 (when a control switch 551, later described, is in position 3) by the cam 380 on the function shaft 350. Contacts 496, associated with cam 380, are closed at approximately the same time as the aforementioned contacts 382 are closed to pulse the solenoids in the simultaneous receiver. Contacts 496 are in series with the latch electromagnet 474, therefore at 65 the same time the solenoids within the simultaneous receiver are energized to effect the setting of the simultaneous Y-levers 452, the electromagnet 474 is energized to release the transfer lever 468. Electromagnet 474 is made to respond more slowly than the solenoids so the 70 Y-levers will always be completely set before the T-levers 75

490 strike them. This delay of the magnet 474 can be accomplished in any of a number of known ways, such as placing two switch actuating portions of cam 380 in slightly staggered relationship or using an electrical delay circuit; but it is to be understood that the Y-levers 452 must be completely set before the T-levers 490 are moved into engagement therewith.

Each T-lever 490 has a tip 498 which engages a notch 502 in an arm 504 of a code device, as for example, a permutation ring 500 shown in Figures 9, 11 and 16. There are five of these rings 500 and when they are rotated to clockwise and counterclockwise positions by the action of T-levers 490 turning in counterclockwise and clockwise directions, one of a plurality (32 in this embodiment) of stop bars 506 will be sprung into a channel of lined-up notches 508 in the five rings. Once one of the 32 stop bars 506 has been selected by dropping into the aligned notches 508, the T-levers 490 may be disengaged from the Y-levers 452 to free the latter for a new selection. The restoring of the T-levers 490 to a position out of engagement with the Y-levers is accomplished in a manner similar to that used in restoring of the T-levers 286 of the sequential selector. A cam 510 at the end of a second function shaft 512 cooperates with a roller 514 at the end of an arm on the transfer lever 468. When the transfer lever 468 is released, its pivotal movement swings roller 514 against the flat side of cam 510 and subsequent rotation of cam 510 causes the transfer lever 468 to be turned counterclockwise a distance far enough to permit the latch lever 486, at the opposite end of the transfer lever shaft 470, to become latched behind the latch end 482 of armature 476.

Rotation of the second function shaft 512 to effect the above described restoration of the transfer lever is accomplished as follows: At the righthand end of the shaft 512, Figure 11, a rotatably mounted spur gear 516 is in mesh with and constantly rotated by an idler gear 518 which in turn is constantly rotated by the train of gear 354 and 356. On the left face of the rotatably mounted gear 516 is a toothed clutch driving element 520 normally out of engagement with a driven clutch element 522. The driven clutch element 522, non-rotatably keyed to and axially shiftable on function shaft 512, is held away from the driving element through the interoperation of a dog 524 rigid on the driven element, and a roller 525 and stop 526 on the aforementioned latch lever 486. The driven clutch element 522 is biased by a compression spring 528 toward the driving clutch element 520 and, when the transfer lever latch lever 486 is released by movement of the armature latch 482, the stop 526 on latch lever 486 moves to release the dog 524 on the sliding clutch element 522 which will axially shift under bias of spring 528 and become engaged with the driving clutch element 520 to cause shaft 512 to rotate counterclockwise.

After the shaft 512 has made one-half a revolution which, as described above, restores the latch arm 486 to its latched position, the dog 524 of the sliding clutch element 522 will strike the roller and stop 526 of latch arm 486, disengagement of the clutch will result and the shaft 512 will cease rotating.

A number of machine operations are performed as a result of rotation of the second function shaft 512 during its one-half revolution but the only purely mechanical one to be dealt with here is the positioning of a type selecting shaft 530. A large gear 532 is rotatably mounted on the shaft 512 and is caused to turn with the shaft by spring pressed friction plates 534, only one of which can be seen in Figure 11. The friction plates are keyed to the shaft 512 and always turn with it. In mesh with the gear 532 is a smaller gear 536 fixed to the type selecting shaft 530. At the left end of the type selecting shaft 530 is a stop arm 538, constructed to rotate inside of the stop bars 506 and to be arrested by any

bar which is selected by dropping into aligned notches of the code rings 500.

It follows then that when the second function shaft 512 starts to rotate, the type selecting shaft 530 will also start to rotate and the latter shaft 530 will continue to rotate until stop arm 538 contacts a selected stop bar 506. The shaft 530 will then stop due to the slippage of the gear 532 on the faces of the friction clutch 534. The type selecting shaft 530 will thus have been rotated to an angular position which corresponds to a type character represented by the code received at the simultaneous receiver.

One other mechanical electrical operation performed by the second function shaft 512 is an important part of this invention. At the righthand end of the function shaft 512 is a cam 540 which cooperates with two normally closed pairs of contacts 542 and 544, opening them at certain timed intervals, and with a pair of normally open contacts 546, closing them at timed intervals. The purpose of each of these pairs of contacts will be disclosed in the description of the overall electric circuit to be hereinafter completely described.

SWITCHING CIRCUIT

25 The switching circuit for interconnecting the machine transmitting and receiving elements into various operating associations is shown in Figure 16. At the right-hand side of the diagram is a three position switch 551 having four independent banks 552a, 552b, 552c and 552d. The three different positions of the switch, as illustrated, allow the following arrangements. It is obvious that additional combinations may be had by adding positions to the switch.

Position 1

Keyboard (simultaneous ending) to reperforator (simultaneous) receiver: This is the *free* keyboard condition of this invention. The operator may manipulate the keyboard at any cadence or rhythm to print and punch tape on the reperforator. This system is diagrammatically illustrated in Figure 17.

Position 2

45 Keyboard (simultaneous sending) to reperforator (simultaneous) receiver. Keyboard (sequential sending) to outgoing line: The operator may work the keyboard to send a message by sequential sending to an outgoing line (which may be a monitoring page printer) and at the same time have the same message punched and printed on tape by the reperforator. The speed at which the 50 keyboard may be operated is limited by the speed of the machines on the outgoing line. This system is diagrammatically illustrated in Figure 18.

Position 3

55 Keyboard (sequential sending) to outgoing line. Reperforator (sequential receiving) from incoming line: The operator may send a message from the keyboard to an outgoing line by sequential signals and at the same time an incoming message may be printed and punched on tape by the reperforator. This system is diagrammatically illustrated in Figure 19.

65 Setting switch 551 in No. 1 position enables the operator to manipulate the keyboard to send simultaneous signals to the reperforator which will print and punch tape. Referring now to Figure 16, sequential signals will not be sent because the sequential transmitter is prevented from operating by the lock solenoid 224. The reperforator will not respond to signals from the incoming line because the common circuit through switch plate contact strip 338 for the solenoids 406, 408, etc. is open at switch contacts 552c(3).

70 With the switch 551 set in No. 1 position, current from battery 550 will energize the coils of lock solenoid 224 at the keyboard through the switch-contacts 552c(1) and

thence back to the negative side of the battery. The keyboard transmitter shaft 58 is thus prevented from rotating so sequential signals will not be sent. Upon the pressing of a key lever 22, the code bars 20 are set in left and righthand positions and the universal bar 80 moves to the right to release the stop lever 92 and to close the contacts 220 and 222. The contacts 222, when closed, will put battery current on the simultaneous receiving circuit as follows: From the positive side of battery 550 through the closed contacts 542 to the common side of the solenoid coils 406 and 408 through the coil and to the "space" contact 178 and "mark" contact 176 of the simultaneous switch at the keyboard; through the sliding switch arm 174 to the switch contact 552b(1) through the closed contacts 222 to the negative side of battery 550. Hence certain "mark" and "space" solenoids in the simultaneous receiver will be energized and the Y-levers 452 will be set accordingly.

The closing of contacts 220, which also occurs when the keyboard transmitter stop lever 92 drops, will set up the circuit to release the reperforator transfer lever 468 by permitting rotation of the reperforator's second function shaft 512. This circuit may be traced as follows: From battery 550 through closed contacts 544, through reperforator latch magnet 474 to switch contact 552a(1) through the contacts 220, to negative side of battery 550. Thus the latch magnet 474 will be energized to pull on the armature latch 476 and release the second function shaft 512. As soon as the function shaft 512 starts to rotate, the cam 540 presents its lobe to the contacts 544 and 542 to open their circuits. Thus the current is taken off the simultaneous receiver solenoids and off the start magnet 474 of function shaft 512.

The function shaft 512 continues to rotate to complete the selecting, printing and perforating of the desired character corresponding to the depressed key lever 22. Shortly before the function shaft 512 is arrested by the latch lever 476, the lobe of the cam 540 closes the contacts 546 and a current pulse is delivered from battery 550 through the switch contact 552d(1), to the coils of the keyboard transmitter restoring solenoid 102 and to negative battery. Thus the restoring solenoid in the keyboard transmitter is pulsed to pull stop lever 92 up into latching position and the contacts 222 and 220 are again opened.

Due to the fact that the receiving reperforator function shaft 512 cycles at a considerably higher speed than an operator can manipulate the keyboard, the transmitter cam stop lever 92 is always restored and in readiness to be released by the depressing of another key lever before another key lever can be depressed. The keyboard is thus practically unlimited in its speed of manipulation.

Setting switch 551 in No. 2 position will permit the operator to work the keyboard to concurrently send sequential signals to the outgoing line and simultaneous signals to the reperforator. The sequential signalling transmitter shaft 58 is permitted to rotate because the lock solenoid 224 is not energized inasmuch as the circuit through contact 552c(2) is open.

When a key lever 22 is depressed, the code bars 20 take their left and righthand positions and the universal bar 80 releases the cam stop lever 92 to permit the keyboard transmitter shaft 58 to turn and close contacts 220 and 222. The closing of the contacts 222 will put current on the simultaneous receiving circuit just as before but in this 2nd position the circuit is through switch contact 552b(2). The start magnet 474 for the reperforator second function shaft 512, will be pulsed by current from battery 550 through contacts 544, through the coil of electromagnet 474 to the switch contacts 552a(2), through the contacts 140 closed by transmitter shaft cam 134 and to negative of battery. The simultaneous receiver then finishes its cycle just as before.

As this No. 2 switch position also sends the keyboard

initiated message to the telegraph line, the sequential transmitter will cycle, having been released as stated above, to transmit the code group. Shortly after the sequential transmitter shaft 58 has started to rotate, restoring solenoid 102 will be energized from battery 550 through contacts 138, also closed by the transmitter shaft cam 134, through the coil 102 to negative battery. The cam stop lever 92 will thus be lifted to its stop position and the stop lever actuated contacts 222 will be opened. The transmitter shaft 58 completes its cycle and stops, awaiting another key lever to be depressed.

In the above described operation, the keyboard manipulating speed is under the control of the sequential transmitter speed due to the locking of the code bars by the sensing levers locking bail 150. This is obviously necessary when transmitting a message to a telegraph line which has a definite predetermined transmitting cadence.

By setting switch 551 in No. 3 position the keyboard can send sequential signals to an outgoing line and the reperforator can receive sequential signals from an incoming line. The simultaneous sending circuit is ineffective because the circuit through common line 210 is open at contacts 552b(3). All other electrical circuits between the keyboard and the reperforator are open when the switch 551 is in No. 3 position. In this condition the keyboard transmits to the outgoing line in the same manner as in position 2.

The reperforator is in condition to receive sequential signals over the incoming line. The reception of a "start" signal will cause the selector magnet 244 to release the receiver shaft 258 which will rotate to position the sliding switches 308. The sliding switches 308 are set in "mark" and "space" positions on the switch plate 324 by the sequential receiving and selecting mechanism and are locked there. The cam 380 then closes contacts 382 which completes a circuit to connect battery 550 to the simultaneous receiving solenoids through the contacts 542 to the common lead to the solenoids, through the coils 406 or 408, to the mark segment 342 and to the space segment 344 of the code bar switching plate 324. For the mark position shown, the circuit proceeds through the contact 308 to the common segment 338, through the contacts 382, to switch contacts 552c(3), to negative battery. The simultaneous receiver 386 is thus energized to set the Y-levers 452.

Cam 380 also closes contacts 496 to place the battery 550 in circuit with the start magnet 474, which circuit is through contacts 544, through the coil of start magnet 474, to switch contacts 552a(3), through contacts 496 and to negative battery. Thus the simultaneous receiver shaft 512 is released, the transfer of the Y-lever settings to the code rings 500 takes place and a printing cycle is completed to record the character identified with the incoming signal.

In the foregoing description and drawings, new printing telegraph equipment has been disclosed which will enable greater versatility between keyboard transmitter units and receiver mechanisms than has heretofore been obtained. The transmission components can concurrently or independently transmit sequential and simultaneous forms of code signal combinations, and will also provide immediate line position indicia for the operator. The transmitter is provided with tabulating mechanism cooperating with the line position indicating mechanism and transmitter start-stop control components to enable rapid tabulation transmission. The receiving mechanism can receive code signal combinations in either sequential or simultaneous form and include a sequential receiver and translator and a simultaneous receiver and translator, the two receivers and translators working in series when receiving sequential signals and only the simultaneous receiver and translator being operative when simultaneous code signal combinations are received. Many combinations of transmitting and receiving equipment can be

realized with this new equipment in addition to standard

page printers for monitoring keyboard transmission or receiving incoming messages and perforated tape transmitters for transmission of stored messages. A disclosed switching system illustrates various arrangements of the sequential-simultaneous keyboard transmitter used with a reperforator embodying the sequential and simultaneous receiver and a standard monitor which may be used with the keyboard. Although the keyboard transmitter operational speed is always limited by the standard line operational cadence, e.g., 60 words per minute, whenever sequential transmission is being accomplished, one arrangement, which uses only simultaneous transmission from the keyboard to the reperforator, bypasses the cadence control required in sequential transmission, resulting in an essentially free keyboard for unlimited speed within the range of a human operator.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Telegraphic communication equipment comprising in combination: a keyboard transmitter with means to transmit both sequential and simultaneous electrical forms of the same code signal combinations; a receiving mechanism with means to selectively receive sequential or simultaneous code signals; and means for selectively providing simultaneous code signal telegraphic communication between the said transmitter and receiver.

2. Telegraphic communication equipment comprising in combination: a keyboard transmitter with means to transmit both sequential and simultaneous code signals; a receiving mechanism with means to selectively receive sequential or simultaneous code signals; means for selectively providing simultaneous code signal telegraphic communication between said transmitter and receiver; said keyboard transmitter including a plurality of key levers and code bars and a shiftably mounted universal bar, with means on said universal bar adapted to be engaged by said key levers enabling said universal bar to be shifted upon depression of a key lever; said transmitting means including a sequential transmitter with a rotating shaft for sequential transmission operation and a start-stop control for said shaft, shaft stop means to block and unblock rotation of said shaft adapted to be moved by said universal bar to unblock said shaft, and means with parallel controls adapted to move said shaft stop means to shaft blocking position upon rotation of said shaft; said transmitting means also including a switch bank with a plurality of circuits to said receiving mechanism and switches adapted to be simultaneously actuated in accord with code bar positioning upon depression of a key lever, and a common circuit to energize all switch circuits including a pulsing switch operable to closed position by movement of said shaft stop means to shaft unblocking position; and a selective control means, including lock means to lock said sequential transmitter shaft against rotation, for placing said means with parallel controls under control of said receiver when the circuits to the receiver are energized by said pulsing switch.

3. Telegraphic communication equipment comprising in combination: a keyboard transmitter with means to transmit both sequential and simultaneous code signals; a receiving mechanism with means to selectively receive sequential or simultaneous code signals; means for selectively providing simultaneous code signal telegraphic communication between said transmitter and receiver; said keyboard transmitter including: a plurality of code bars, each shiftable to one of two positions in accord with

a desired code signal combination; a plurality of two position switches; means connecting individual switches to corresponding code bars for movement to one of said two positions in accord with code bar positioning; two

5 independent circuits from each of said two position switches corresponding to the two positions; means under control of said keyboard transmitter for pulsing all circuits set up by positioning of said two position switches; and a sequential transmitter operated and controlled by

10 positioning of said code bars.

4. Telegraphic communication equipment comprising in combination: a keyboard transmitter with means to transmit both sequential and simultaneous code signals; a receiving mechanism with means to selectively receive sequential or simultaneous code signals; means for selectively

15 providing simultaneous code signal telegraphic communication between said transmitter and receiver; said keyboard transmitter including: key levers; code bars; a universal bar invariably positioned by key lever depression; code bar sensing levers positioned by said code bars; selector levers adapted to be blocked or unblocked by said sensing levers; a rotatable cam shaft having a stop and cams for sequentially actuating said selector levers; a set of contacts disposed to be opened or

25 closed by cam operation of said selector levers dependent upon blocking or unblocking of said selector levers by said sensing levers; cam stop means movable into and out of the path of rotation of said stop, adapted to be engaged by said universal bar to be shifted out of the path of rotation of said stop; power means for moving said cam stop

30 means back into the path of rotation of said stop; means for controlling operation of said power means selectively responsive to camshaft rotation and to reception of a simultaneous code signal combination by said receiver; and a simultaneous transmitter operated and controlled by positioning of said code bars including means actuated to transmit a code signal combination by movement of said cam stop means out of the path of rotation of said stop.

40 5. Telegraphic communication equipment as defined in claim 4, wherein said keyboard transmitter includes: a means to block repeat transmission; means for disabling said repeat transmission blocking means; a tabulating mechanism including tab stops and a line position indicating mechanism, operated one spacing indicia by said power means each time a code signal combination causing a spacing operation is transmitted, adapted to be automatically actuated by continued joint operation of a key lever and said means for disabling said repeat blocking means; and means controlled by interoperations of said tab stops and said indicating mechanism to control operation of said power means and block further repeat transmission.

6. Telegraphic communication equipment comprising

55 in combination: a keyboard transmitter with means to transmit both sequential and simultaneous code signals; a receiving mechanism with means to selectively receive sequential or simultaneous code signals; means for selectively providing simultaneous code signal telegraphic

60 communication between said transmitter and receiver; said receiver including: a sequential receiving means comprising a mechanical means for storing sequential code signal combinations; a code signal device bank including a plurality of two position signal devices equal in number to the code signals in said code signal combinations;

65 means for simultaneously transferring said stored received signals to positions in said code signal device bank; a mechanism for simultaneously receiving a code signal combination and translating said code signal combination into a mechanical operation; and means selectively operative to actuate said simultaneous receiving and translating mechanism from said code signal bank or from said keyboard transmitter including means rendering said sequential receiving means inoperative upon se-

70

75

lection of actuation of said simultaneous receiving and translating mechanism by said keyboard transmitter.

7. Telegraph communication equipment comprising: a keyboard transmitter having means for sequential and simultaneous code unit combination transmission; a receiving mechanism having means for receiving code unit combinations in sequential or simultaneous form and translating them into mechanical operations; coordinated control means operatively connecting said transmitter and receiver whereby concurrent sequential and simultaneous transmission can be sent from said transmitter with the simultaneous transmission received by said receiving mechanism under time control of said transmitter, and simultaneous transmission by said transmitter can be received by said receiver to the exclusion of sequential transmission whereby transmission speed is controlled by said receiver.

8. Telegraphic communication equipment comprising: a keyboard transmitter having means for transmission of sequential and simultaneous forms of the same code unit combination; a receiving mechanism having means for receiving code unit combinations in sequential or simultaneous form and translating them into mechanical printing operations; coordinated means operatively connecting said transmitter and receiver so simultaneous transmission by said transmitter can be received by said receiver and including lockout means to prevent sequential transmission by said transmitter and means to place maximum transmission speed of said transmitter under control of said receiver.

9. Telegraphic communication equipment, adapted to be connected to a signal line, comprising: a sequential and simultaneous keyboard transmitter mechanism; a sequential and simultaneous receiving mechanism; switching control means connecting said keyboard transmitter and receiver mechanisms whereby a number of different forms of telegraph operation can be realized, including sequential line transmission from said keyboard transmitter with simultaneous transmission to said receiving mechanism during the same line transmission operation; sequential line transmission from said keyboard transmitter to one line with sequential reception by said receiving mechanism from a second line occurring at the same time; and simultaneous code unit transmission only, from said keyboard transmitter connected directly to the simultaneous receiving portion of said receiving mechanism.

10. Telegraphic communication equipment comprising: a keyboard transmitter having means to transmit sequential code signals and/or simultaneous code signals; a sequential and simultaneous code signal receiver translator mechanism; a switching system control means, operatively connecting said keyboard and receiver translator; means in said keyboard transmitter under control of said switching system control means providing start and stop control of signal combination transmission during any keyboard sequential transmission; and means in said keyboard transmitter and receiver under control of said switching system control means providing the start and stop control, during solely simultaneous keyboard transmission and reception between said keyboard transmitter and receiving translator mechanism, to be partially in the receiver mechanism.

11. Telegraphic communication equipment comprising: a keyboard transmitter having means to transmit sequential code signals and/or simultaneous code signals; a sequential and simultaneous code signal receiver translator mechanism; a switching system control means, operatively connecting said keyboard and receiver translator; sequential transmitting means in said keyboard transmitter including a rotatable shaft and shaft operated means under control of said switching system control means providing start and stop control of keyboard signal transmission during any keyboard sequential transmission; and means in said keyboard transmitter and receiver under control of said switching system control means

providing stop control of keyboard signal transmission during solely simultaneous keyboard transmission.

12. Telegraphic communication equipment comprising in combination: a keyboard transmitter with means to transmit sequential code signal combinations to a conventional signal circuit and selective means, including a multi-line circuit, to enable transmission of simultaneous code signal combinations concurrently or independently of said sequential code signal transmission over said 10 multi-line circuit; and a receiving-translating mechanism with means connected to receive simultaneous signals from said multi-line circuit.

13. Telegraphic communication equipment comprising in combination: a keyboard transmitter with means including a multi-line circuit to transmit simultaneous code signal combinations; and a receiving translating mechanism with means to selectively receive both sequential and simultaneous forms of code signal combinations, including means connected to receive simultaneous code signal 20 combinations from said multi-line circuit.

14. Telegraphic equipment as defined in claim 13 wherein, said receiving-translating mechanism includes a sequential receiver and a simultaneous receiver with means in series between said sequential receiver and said 25 simultaneous receiver providing transfer of sequentially received code signal combinations to said simultaneous receiver for translation to mechanical operations.

15. Telegraphic communication equipment comprising: a keyboard; and transmitter means operatively connected with said keyboard including means for transmitting simultaneous and sequential forms of electrical code signal combinations, concurrently and independently.

16. Printing telegraph equipment comprising: a keyboard with key levers; code means set in predetermined 35 pattern by operation of said key levers; transmitter means operatively connected with said code means including means for transmitting simultaneous and sequential forms of code signal combinations; and selective means enabling concurrent and independent, simultaneous and sequential 40 transmission.

17. A keyboard transmitter for use with a simultaneous code signal combination receiver comprising: a code means adapted to be positioned in a predetermined pattern for each desired code signal combination; means to simultaneously transmit all signals of each code signal 45 combination, operable immediately upon positioning of said code means; and means, adapted to be controlled by said receiver, permitting a repositioning of said code means for transmission of a subsequent code signal combination substantially immediately after the receiver receives and translates the simultaneous transmission.

18. A keyboard transmitter comprising: a plural key keyboard; a simultaneous transmitter having a switch bank including a plurality of switches under simultaneous control of keyboard selection; a sequential transmitter including a rotatable cam shaft, a plurality of selecting lever cams on said cam shaft, selector levers operated by said cams, a sequential code transmitting switch under control of said selector levers, and means enabling cam shaft rotation under control by keyboard selection; and a pulsing circuit in parallel connection with all of said switches in said switch bank including a switch means for completing said pulsing circuit adapted to be invariably operated upon keyboard code bar operation.

19. A keyboard transmitter comprising: a plurality of selectively permutatably positionable code bars; a simultaneous transmitter having a switch bank including a plurality of two position switches under simultaneous control of keyboard code bar positions; a sequential transmitter including a cam rotatable shaft, a plurality of selecting lever cams on said cam shaft, a sequential code transmitting switch and a plurality of selecting levers under control of keyboard code bar positions and operated by said cams; and a pulsing circuit in parallel connection with all of said switches in said switch bank

including a switch means for completing said pulsing circuit adapted to be invariably operated upon keyboard code bar operation.

20. A keyboard transmitter comprising: code bar operating key levers; a plurality of code bars shiftable upon operation of any code bar key lever, a sequential transmitter including a rotatable cam shaft having a stop member thereon; a cam shaft stop lever for engagement with said stop member; means to invariably release said stop lever from stop position upon operation of any code bar key lever; and means, including a solenoid energized prior to completion of one cycle of cam shaft operation, to replace said cam shaft stop lever in engagement with said stop member.

21. A keyboard transmitter comprising: code bar operating key levers; a plurality of code bars shiftable upon operation of any code bar lever; a sequential transmitter including a friction driven rotatable cam shaft having a stop thereon; a pivoted cam shaft stop lever invariably released from cam shaft stop position upon operation of any code bar key lever; and electrical power means enabled by rotation of said cam shaft and adapted, when enabled, to engage and pivot said cam shaft stop lever into a position of engagement with said stop.

22. A keyboard transmitter as defined in claim 20, comprising: a character and space position indicating mechanism with an indicator, and a tabulating stop mechanism; mechanism including a means operatively coupled with said cam shaft stop lever for shifting said space counting indicator carriage one space for each cycle of cam shaft stop lever operation adapted to be disenable during keyboard transmission of certain code signal combinations; abutment means on said indicating mechanism adapted to be engaged by a portion of said tabulating stop mechanism and including switching contacts and a parallel control circuit for said electrical power means whereby upon said engagement of said abutment means, said electrical power means will be energized to terminate further keyboard transmission tabulating operation after a desired tabulating stop position is reached by said indicating mechanism.

23. A transmitter as defined in claim 22 wherein, the electrical power means control circuit has parallel control leads adapted to be controlled by a receiving mechanism whereby said electrical power means can be controlled by receiver operation to the exclusion of control by transmitter operation.

24. A keyboard transmitter with tabulator mechanism comprising: a transmitter stop member invariably operated for each transmission of a code signal combination, a line space indicating mechanism with a traversing member; a tabulating stop mechanism with a plurality of positionable stops; means on said traversing member adapted to engage a positioned tab stop at a line space position corresponding to the positioned tab stop; an operating means for said transmitter stop member; a control for said operating device actuated by engagement of said means on said traversing member with a tab stop to operate said transmitter stop member and cause transmitter operation to be terminated at a line position determined by the positioned tab stop.

25. A transmitter as defined in claim 24, wherein: said operating means is a solenoid, operatively connected with said transmitter stop member; and said control is a solenoid control circuit with a series switch adapted to be closed upon engagement of said traversing member with any positioned tab stop.

26. A tabulator mechanism for use in combination with a keyboard transmitter having key levers and associated controls including a repeat key lever and a transmission stop device comprising: a two-position member with a normal position, invariably shifted away from normal position upon actuation of said repeat key lever; a tabulator stop frame including a plurality of shiftable tab stops; means pivotally mounting said tabulator stop frame on the keyboard transmitter for pivotal movement

between a normal position and a second position where selected tab stops are in an operative position; linkage between said two-position member and said tabulator stop frame enabling movement of said tabulator frame to its second position upon actuation of said repeat key lever; and means indicative of line space position, engageable with an operative selected tab stop, and having a control connection with said transmission stop device to cause cessation of repeat transmission upon engagement with an operative selected tab stop.

27. A tabulator mechanism as defined in claim 26 wherein, the linkage between said two-position member and said tabulator stop frame includes a resilient connector; and a shiftable latch member is disposed to be moved into latching engagement with and maintain said tabulator stop frame in its normal position to thereby disenable tabulator operation when said repeat key lever is actuated.

28. A tabulator mechanism for use in combination with a keyboard transmitter as defined in claim 26 wherein: said keyboard transmitter includes a carriage return key lever; said two-position member includes means for blocking actuation of said carriage return key lever, rendered operable when said two-position member is shifted away from normal position by actuation of said repeat key lever.

29. A keyboard transmitter comprising: a transmitter stop member invariably operated for each transmission of a code signal combination; a character and space counting and position indicating carriage; a tabulating stop mechanism with a plurality of positionable stops; stepping means controlled by said transmitter stop member for shifting said indicating carriage one space for each cycle of operation of said transmitter stop member; means providing for said stepping means to be disenable during transmission of certain code signal combination; means including a projecting means on said carriage adapted to engage a positioned tab stop and an operable control device for said transmitter stop member whereby, upon engagement of said projecting means with a tab stop, said transmitter stop member will be operated to cause transmitter operation to be terminated at a line position determined by the positioned tab stop.

30. A keyboard transmitter as defined in claim 29 wherein, said means including a projecting means on said carriage comprises: two contact strips parallel to and adjacent the path of said carriage; a dielectric member pivoted on said carriage; a contact bridge fastened to said dielectric member adapted, upon pivotal movement of said dielectric member, to bridge between said two contact strips; means resiliently biasing said dielectric member to a position where said contact bridge is out of engagement with said contact strips; a finger attached to said dielectric member eccentric to its pivot axis and disposed to move in a path determined by indicator carriage movement where said finger will abut a positioned tab stop and rotate said dielectric member to cause bridging of said contact strips.

31. In combination with a keyboard transmitter having an electrically controlled transmitter stop device with a control circuit, a tabulator mechanism comprising: a shiftable frame carrying a plurality of independently pivotable tab stop levers movable between selected and unselected positions; means for shifting said frame to a tabulation operable position; a carriage, movable laterally in front of said frame adjacent said tab stop levers in accord with transmitter operations, having a pivotable dielectric portion carrying a contact bridge and a projecting member eccentric to the pivot axis of said dielectric portion, said path of movement of said indicating carriage being such as to move the projecting member in a path to engage a selected tab stop lever when said frame is in its tabulation operable position; and parallel contacts in series connection with said control circuit disposed adjacent the path of movement of said contact bridge and adapted to be engaged and bridged by said

contact bridge upon pivotal movement of said dielectric portion when said projecting member engages a selected and positioned tab stop lever, so the transmitter operation will terminate upon tabulation transmission reaching a position determined by tab stop position.

32. For use in combination with a code bar keyboard transmitter, a character and space transmission indicating device comprising: a line space indicia scale; an indicating carriage mounted for lateral translation along said indicia scale; stepping means for moving said indicating carriage a distance equal to one space indicia in a direction from start-of-line position to end-of-line position responsive to each keyboard transmission involving a spacing function; means for storing power to return said carriage to a start-of-line position as it moves toward the end-of-line position; means disengaging and locking said stepping means and enabling indicating carriage movement toward start-of-line position under force of said stored power means; means engaged and actuated by said carriage, upon its reaching a start-of-line position, for stopping carriage movement at the exact start-of-line position, and unlocking said stepping means to return control of carriage movement to said stepping means; a tabulating mechanism including a movable switch contact member on said carriage, and a plurality of selectable stops positionable in the path of translation of said movable switch contact member on said carriage; and a control circuit, adapted to be connected to electrical transmitter stop mechanism, completed by movement of said movable switch contact upon its engagement with a selected stop positioned in the path of translation of said movable switch contact member.

33. Printing telegraph equipment comprising: a transmitter operator device including a plurality of code means and means for setting said code means in a predetermined pattern representative of data indicative signal element combinations; transmitter means operatively connected with said code means including means for transmitting simultaneous and sequential forms of the same code signal combinations; and selective means enabling concurrent and independent, simultaneous and sequential transmission.

34. Telegraphic communication equipment comprising in combination: a transmitter with means to concurrently transmit both sequential and simultaneous forms of the same code signal combinations; a receiving mechanism with means to selectively receive sequential or simultaneous code signals; and means for selectively providing simultaneous form of code signal combination telegraphic communication between said transmitter and receiver.
